Primary Examiner — Michael A Pratt

(57) **CLAIM**

The ornamental design for an imitation bolt carrier with ammunition cartridge, substantially as shown and described.

DESCRIPTION

FIG. 1 is an upper right front perspective view of the device;
FIG. 2 is a lower left front perspective view of the device;
FIG. 3 is an upper left rear perspective view;
FIG. 4 is a lower right rear perspective;
FIG. 5 is a right elevation view;
FIG. 6 is a left elevation view;
FIG. 7 is a top view;
FIG. 8 is a bottom view;
FIG. 9 is a back elevation view; and,
FIG. 10 is a front elevation view.
